I. N. FORRESTER AND JAMES H. LUDDINGTON, OF BRIDGEPORT,
CONNECTICUT.

Letters Patent No. 85,577, dated January 5, 1869.

IMPROVEMENT IN PUMPS.

The Schedule referred to in these Letters Patent and making part of the same.

To all whom it may concern:

Be it known that we, I. N. FORRESTER and JAMES H. LUDDINGTON, of Bridgeport, in the county of Fairfield, and State of Connecticut, have invented a new and improved Pump; and we do hereby declare that the following is a full, clear, and exact description thereof, which will enable others skilled in the art to make and use the same, reference being had to the accompanying drawings, which represent a vertical central section of our improved pump.

This invention relates to a pump of that class in which the pump-cylinder is made movable around a stationary piston; and

Its object is to make the central discharge-tube stationary, so that the water-pipe can be attached to it at any desired place, and do away with the wooden supports in the well.

The object of the invention is also to produce a convenient valve-arrangement, which will allow the apparatus to be worked with but little friction.

The invention consists in the use of a hollow piston, fitted around the stationary central discharge-tube, in such manner that it communicates with the same, and arranged within a cylinder that is suspended from a rod, and suitable lever-arrangement, by means of which reciprocating motion can be imparted to it.

The piston and cylinders are provided with a series of valves, by means of which the influx of water within the pump is regulated, so that a continuous stream will be produced.

A, in the drawing, represents a metal tube, with a closed lower end, standing on the bottom of the well.

This tube forms the guide of the pump-cylinder B, which is fitted around it, and supports, also, the hollow piston C, with which it communicates.

The tube is perforated within the piston, as shown, so that the water can readily pass from the piston into the tube.

The piston fits well against the side of the cylinder,

which is suspended from suitable levers, or other pumping-mechanism, by means of a rod, D.

In the upper head, a, of the cylinder, is fitted a valve, b, and in the lower head, c, is arranged a valve, d.

The heads of the hollow piston are also perforated to permit motion to a double-acting valve, e, which is arranged within the said piston, as shown.

When the cylinder is moved downward, the head a will be moved against the piston, and its valve, b, will consequently be closed, while the valve e will close the aperture of the lower head, g, of the piston, while that of the upper piston-head, f, will remain open.

The fluid contained in the upper compartment of the cylinder will thus, during the downward motion of the latter, be forced into the piston, and thence into the pipe A, as indicated in the drawing. The lower compartment of the cylinder will, at the same time, be filled with fresh water, the valve d being opened, as shown.

When the motion of the cylinder is reversed, that of the water will also be, as then the valve b is opened and d closed, while e will close against the upper piston-head, f. The water will then be forced into the piston from the lower compartment of the cylinder, while the upper compartment of the same will be refilled.

Having thus described our invention,

We claim as new, and desire to secure by Letters Patent—

The pump, consisting of the movable cylinder B, which has the valves b and d, and of the stationary piston C, secured to and communicating with the supporting-tube A, and provided with the double-acting valve e, all made, combined, and operating substantially as herein shown and described.

I. N. FORRESTER.

J. H. LUDDINGTON.
